LUBRICATION SYSTEM FOR POWER HEADS
AND THE LIKEChristopher Groen, Dubuque, Iowa, assignor to
A. Y. McDonald Mfg. Co., Dubuque, Iowa, a cor-
poration of Iowa

Application December 27, 1932, Serial No. 648,894

2 Claims. (Cl. 184—11)

This invention relates primarily to a lubrication system which is adapted for certain classes of machinery, notably a power head for operating a deep well pump. The features of improvement inherent in my invention were first disclosed in my power head application, Serial No. 580,929, which I filed December 14, 1931.

It is a primary object of this invention to provide a simplified, yet positive, means by which 10 to feed a lubricant to a selected point in a power head mechanism, as, for example, a distributing center from which oil may flow or drop to various places requiring more or less constant lubrication. Such a system should be dependable in operation, 15 require no attention or adjustments, and involve only the minimum of expense, number of parts, etc. These various objectives are attained by my improved lubrication system which utilizes gear mechanism for lifting oil from a reservoir on to a 20 pinion along whose horizontal shaft the oil is then flowed through a spiral groove to be then forced radially and upwardly to a center for distribution to various points requiring lubrication, the oil feed being maintained continuously and 25 positively as long as the gear mechanism is in operation.

An exemplification of the invention is clearly illustrated in the accompanying drawings in which—

30 Figure 1 is a side elevation of a power head, partly broken out, to illustrate parts that would be otherwise hidden from view;

Fig. 2 is a view partly in rear elevation and partly in vertical longitudinal section, with certain parts broken away, the line of section being indicated at 2—2 of Fig. 1;

Fig. 3 is a view partly in plan and partly in horizontal section taken on line 3—3 of Fig. 1;

Fig. 4 is a detail vertical section through the 40 transbearing bracket, taken on line 4—4 of Fig. 3;

Fig. 5 is a view partly in plan and partly in horizontal section of the oil distributor and transbearing bracket taken on line 5—5 of Fig. 1; and

45 Fig. 6 is a fragmental vertical longitudinal section of the pump mechanism, taken on line 6—6 of Fig. 3.

Referring to the drawings which illustrate one embodiment of the invention I have shown an 50 open-topped casing 6 rounded in its bottom and supported upon feet 7 which may be bolted or otherwise secured to the platform of a well in the usual manner. The feet are connected substantially to the casing as by flanges or webs 8.

55 The rear of the casing has a reentrant wall 9

the contour of which conforms generally to two spaced gears which are mounted within the casing. Extending centrally between the front and rear walls of the casing is a bracket 10. At one side of the casing is shown a filler pipe 11, closed by a screw plug through which fluid lubricant may be introduced, a drain opening, closed by a plug 12, being located desirably at the opposite side of the casing.

Bolted or otherwise secured to the feet of the 65 casing is a discharge head 14 from which may depend a drop pipe 15 for connection with a pump cylinder (not shown). The piston rod 16 which operates the pump extends through a stuffing box 17 in the top of the discharge head, 70 upon which I may also mount an air pump 18 having its plunger stem 19 connected to the piston rod by a bracket arm 20.

The upper end of the piston rod is detachably connected to a cross head 21 which is reciprocated 75 by suitable power mechanism. By disconnecting the piston rod from the cross head and the discharge head from the feet of the casing, the piston rod and connected parts may be shifted rearwardly of the casing permitting withdrawal from the well of the pump cylinder assembly. This may be accomplished without disturbing the power head setting in any degree due to disposition of the piston rod within the space defined 80 by the reentrant walls of the casing, but exteriorly 85 thereof.

The trans-bearing bracket is bored to provide bearings 22 and 23 in which are journaled, respectively, a drive shaft 24 and a driven shaft 25 having intermeshing pinions 26 and gears 27. 90 The side walls of the casing may be provided with openings in line with the bearing apertures to facilitate preparation of the bearings and insertion of the shafts therein, plugs 28 being thereafter applied to the openings by friction to close 95 the same.

The driven gears 27 which are made fast to the shaft 25, as by set screws 29, also function as crank wheels. They are provided with several oppositely disposed bosses 30 adapted to receive 100 wrist pins 31 to provide connections with pitmen 32 which are pivotally joined to the cross head 21. The several pairs of bosses 30 are spaced at different radial distances from the axis of the crank wheels to provide for variation in the stroke 105 of the pitmen.

Inasmuch as the crank wheels are confined in restricted spaces in the casing, I have devised a novel wrist pin assembly for each pitman. As shown, each wrist pin is formed with a head 110

which bears against the boss 30. The shank of the pin extends through a bushing 33 which is fitted within the bearing aperture in the pitman, a castellated nut 34 being threaded upon the pin end, as shown.

6 The bearing face of the pitman is provided with an oil groove 35 through which lubricant may be distributed over its entire surface in engagement with the bushing. Pins 36 rigidly secured in co-axial alignment with each other in the cross head 21 project from the ends thereof to enter apertures in the upper ends of the pitmen. The pitmen are held in place on the pins 36 as by washers and cotter pins 37.

15 As by bolts and nuts 39 I connect to the cross head a clamp block 38, the piston rod 16 being received within seats between these parts, and there held by the friction resulting from tightening of the clamp block. Above the cross head the piston rod may be screw-threaded for connection with a windmill rod or other device, as desired.

20 For the cross head I provide an upstanding guide which may take the form of a pair of rods 40 having their lower ends 41 anchored within sockets in the casing (see Fig. 2). At their upper ends the guide rods are connected by a block 42 to a hollow brace rod 43, the lower end of which is anchored to the trans-bearing bracket 13 as at 44 (see Fig. 6), the upper ends of the guide rods being thereby rigidly supported. The guide and brace rods extend through the block 42 and are threaded to receive nuts 54 and 55 by which the block is clamped fixedly in place between the guide rods and brace rods.

25 A positive and simple oiling system has been provided for supplying lubricant to all of the moving parts of the present mechanism. This includes a pump which is incorporated with and made a part of the transmission. A quantity of fluid lubricant is contained in the bottom of the casing to a level which contacts with the crank gears. In operation, the teeth of the gears carry some of the oil to the pinions 26. At this point, some of the oil is expressed from between the teeth for travel to other places which require lubrication.

30 As shown, oil inlet ports or passageways 45 are formed at the ends of the drive shaft bearing, these passageways being located adjacent the sides of the pinions 26 which receive oil from the crank gears (see Fig. 3). Some of the gear-lifted oil flows along the trans-bearing bracket on opposite sides of a central web 46 to oil holes 47 located above the driven shaft 25. The trans-bearing bracket is sloped inwardly towards its central web and also longitudinally toward the bearing for the crank gears, as shown in Figs. 2 and 4, thereby providing shallow troughs through which the oil flows in a pre-arranged manner.

35 The oil pump mechanism is incorporated with the drive shaft 24 by forming therein oppositely pitched spiral grooves 48 which join with an annular groove 49 intermediately of the shaft ends. Other annular grooves 50 also joining with opposite ends of the spiral grooves are provided in the drive shaft at points in register with the passageways 45. A discharge port 51 (see Fig. 6) is arranged in the bearing at a point which registers with the intermediate groove 49, and at this same point the hollow brace rod 43 is anchored to form a conduit leading therefrom to the block 42 which serve as an oil distributor. Oil entering the passageways 45 is fed through spiral grooves to the discharge port 51 to be forced upwardly therefrom through the hollow brace rod

and out upon the overhead oil distributing block.

Formed in the upper surface of the block is an oil channel 52 having two branches that lead to points adjacent the sides of the guide rods for discharge of oil into shallow cups 53 formed in the upper face of the cross head. Each cross head cup surrounds one guide rod to assure adequate lubrication thereof. The excess of oil discharges over low dams and through channels at the ends of the cross head to flow to the pins 36 in which are oil grooves for distributing the oil lengthwise thereof. Additional oil will either drip down or flow along the pitmen to lubricate the wrist pins on the crank gears. The flow of the oil which is governed to some extent by the pitch of the spiral grooves in the drive shaft should be sufficient for continuous delivery to the overhead distributor and points therebelow to lubricate the cross head and all associated parts.

40 Power is applied to the drive shaft 24 from any convenient power source, such as an electric motor 56. Desirably a motor base 57 is provided which, in the form shown, is a rectangular plate secured slantingly above the front wall of the casing by bolts 58. Brace bars 59 may connect the upper end of the motor base fixedly to the casing side walls in the manner shown. The drive shaft 24 which extends out through an opening in a side wall of the casing is equipped at its ends with a pulley 60 around which is trained a belt (or belts) 61 that passes over a belt pulley 62 mounted on the motor shaft. The motor is adjustably carried upon its base and by means of an adjusting screw 63 may be shifted to tighten the belt as required.

45 In order to enclose the power mechanism, a hood 64, preferably formed of sheet metal, is rested upon a ledge surrounding the upper edge of the casing. The hood extends upwardly inside of the motor base to a point slightly above the oil distributor block. A clamped cap 65 rests upon the upper open end of the hood and may be clamped thereon by a pair of nuts 66 threaded upon the upper ends of the guide rods and bearing against the cap. By removing the cap, the hood may be lifted from the casing without disturbing the motor base or any other parts, thus making the entire operating mechanism accessible from all sides.

50 I provide also means which store up energy during the down stroke of the cross head and utilize the stored up energy during its upward or lifting stroke. For this purpose I employ a pair of coiled compression springs 67 encircling the guide rods and confined under tension between the cross head and the bearing adjacent the lower ends of the guide rods. The springs, the same as the associated working parts, are enclosed entirely within the casing and hood.

55 The guide rods are disposed equi-distant from the piston and are arranged in line therewith in order that the springs may exert a balanced pressure against the cross head. It will be noted that the driven shaft is located close to the guide rods and piston rod, so that on the upward stroke the pitmen's thrust will be nearly in line with the pitmen's guides. These springs are lubricated constantly by the oil fed from above, and so will operate with a minimum of friction.

60 I claim:

1. In means to lubricate power heads and the like, the combination with a casing adapted to contain a quantity of fluid lubricant, of two parallel shafts, one slightly higher than the other and each rotatable about its own axis, intermeshing
